UNITED STATES PATENT OFFICE.

MATTHEW J. McCLARENCE AND LAWRENCE B. THURLOW, OF MUNCIE, INDIANA.

DESIGN FOR A SIGN-PLATE.

40,480.

Specification for Design.

Patented Feb. 1, 1910.

Application filed April 9, 1909. Serial No. 489,006. Term of patent 7 years.

To all whom it may concern:

Be it known that we, MATTHEW J. McCLARENCE and LAWRENCE B. THURLOW, both citizens of the United States, and each residing at Muncie, in the county of Delaware and State of Indiana, have invented a new, original, and ornamental Design for a Sign-Plate, of which the following is a specification, reference being had to the accompanying drawing, forming part hereof.

The figure is a front view of a sign plate, showing our new design.

We claim:

The ornamental design for a sign plate, as shown.

MATTHEW J. McCLARENCE.
LAWRENCE B. THURLOW.

Witnesses:

THOMAS L. RYAN,
ETHEL L. LISTER.
